UNITED STATES PATENT OFFICE.

OTTO S. WADE, OF VALPARAISO, INDIANA.

LIGHTING FIXTURE DISPLAY SYSTEM.

Application filed July 31, 1924. Serial No. 729,293.

My invention relates to improvements in lighting fixture display systems and it more especially consists of the features herein-after pointed out in the annexed claims.

5 The purpose of my invention is to provide an effective and simple system for efficiently displaying lighting fixtures in or under harmonious surroundings removed from the usual surfeit of different types and 10 designs of fixtures grouped near each other; that provides a storage room which is isolated from display rooms; that utilizes a group of interconnected storage tracks and interconnected display tracks both joined to 15 a common transfer track; that automatically completes the necessary circuit connections so that each fixture as soon as it is positioned within the desired display room illuminates the fixture so that a prospective 20 purchaser is able to judge of the merits of a given fixture in its relation to the size of the room, its furnishings etc., without being distracted by the proximity of other styles 25 of fixtures; and that enables the salesman to quickly show fixtures in rapid succession for use in parlor, sitting room, living room, kitchen, bath room, etc., etc. In this way a 30 customer can make a more judicious selection than would otherwise be possible.

With these and other ends in view I illustrate in the accompanying drawing such instances of adaptation as will disclose the broad underlying features of my invention without limiting myself to the specific 35 details shown thereon and described herein.

Figure 1 is a diagrammatic plan view showing the relation of tracks to the storage and display quarters.

Fig. 2 is a side elevation of a fixture carrying trolley.

Fig. 3 is a diagrammatic end elevation of Fig. 2.

Fig. 4 is a top plan view of Fig. 2.

Fig. 5 is a modified arrangement of trolley contacts.

In practically carrying out my invention I may use any desired form of traveling trolley which is adapted to support in a detachable and attachable manner lighting fixtures or other similar articles. I may arrange the storage, transfer, and display tracks as the exigencies of actual practice may demand.

The expedients I exemplify in the accompanying drawings are only instances of adaptation which disclose one way in which

my invention can be carried into practice. A storage room 1 is provided with a suitable arrangement of storage tracks 6. These tracks are interconnected with each other 60 and are joined by a transfer track 7 to the display rooms. As a matter of fact the storage and display rooms may be located apart from each other as shown or they may be adjacent each other separated only by a 65 partition. The display rooms may comprise a large room 2, an intermediate sized room 3 and a small sized room 4. In addition a hallway 5 is also shown diagrammatically in Fig. 1. This diagram does not show all 70 of the various rooms heretofore mentioned.

In the display rooms display tracks 8 are interconnected and joined to the transfer track 7. Any desired form of supporting trolley may be used, that is a separate trolley for each fixture placed on display so that more than one fixture can be simultaneously shown in a single room. The trolley I have instanced simply consists of a pair of grooved wheels 10 rolling on the 80 tracks 6, 7 or 8. Each wheel has a U-shaped frame 11 and both frames 11 at the top may be joined by a lengthwise member 12. On this member 12 a cross member 23 may be fixed, which at its ends carries insulated contacts 15. The frames 11 opposite the wheel pivots may also be connected by a lengthwise frame 18. The frames 11 drop beneath the tracks 8 at one side thereof and they are bent over as shown in Fig. 3 so as to form 90 a centrally positioned support for a pan 13. Beneath the pan 13 a hook 14 may be located from which any desired fixture may be suspended by its chains 17 or otherwise.

Each of the contacts 15 may be joined to the lighting fixture wires by-connections 16 in any suitable manner with spring clips (not shown) or otherwise so as to facilitate easy connection and disconnection of the circuit should another fixture be placed on the 100 same trolley later on for another purpose. Display stations 21 may be located in each room at one or more locations as desired. Alongside each display station contacts 9 supported by suspensions 19 may be located 105 to automatically connect the lamps of a fixture with a live circuit as soon as its supporting trolley is brought adjacent the contacts.

If desired the short contacts 9 may be 110 replaced by long contacts 22 these being adapted to show the fixture in a change of

location within the room itself. Eyes 20 may be formed beneath the pan 13 in order to afford means for easily drawing the trolley from place to place by any desired form of hook. The tracks 8 may have a return portion 24 which will facilitate the return of fixtures that have been on display without conflicting with other fixtures brought in later for exhibit purposes. The tracks 6, 7, 10 8 and 24 may be supported by side brackets 25 or in any other well-known manner. The arrangement of contacts 9 and 15 shown in Fig. 3 may be modified as desired so as to bring them into smaller compass without departing from the spirit of my invention, 15 as shown in Fig. 5.

What I claim is:

1. In display systems, a plurality of inter-connecting tracks, a storage room for a portion of said tracks, a plurality of display rooms for another portion of the tracks, a traversing trolley adapted to support lighting fixtures in a detachable and attachable manner, electrical contacts at different points placed adjacent the tracks, insulated contacts on the trolley adapted to co-act with the other contacts, and connections from the latter to the suspended lighting fixture.
2. In display systems, a storage compartment, a plurality of display compartments, interconnecting tracks in each compartment, a transfer track between the compartments, electrical contacts at different locations adjacent the tracks, a trolley adapted to traverse the tracks, cooperating contacts on the trolley

40 ley, and means for supporting a lighting fixture from the trolley in electrical connection with the trolley contact.

3. In display systems, a storage compartment containing lighting fixtures, a display compartment adapted to receive individual fixtures from the storage compartment, interconnected tracks in the compartments, traversing means on the tracks adapted to support individual lighting fixtures, and means for illuminating the fixtures at prearranged points in the display compartment.

4. In display systems, a plurality of display compartments, interconnected tracks within the compartments, a leading-in track connected therewith, a return track connected with the other tracks, means traversible on the tracks adapted to support lighting fixtures, and stationary means placed adjacent the tracks adapted to cooperate with the traversing means to automatically convey current to the lighting fixture at predetermined points.

5. In display systems, a storage room, a display room, a traversing trolley, a track therefor between the rooms, means for supporting a lighting fixture from the trolley, stationary contacts adjacent the tracks at predetermined points in the display room, and cooperating contacts on the trolley adapted to establish electrical connections between the stationary contacts and the lighting fixture.

In testimony whereof I affix my signature.

OTTO S. WADE.
